United States Patent [19]

Gamm

[11] Patent Number: Des. 280,778

[45] Date of Patent:  Oct. 1, 1985

[54] POCKETED BOOT

[75] Inventor: Robert J. Gamm, St. Louis, Mo.

[73] Assignee: Kangaroos U.S.A., Inc., St. Louis, Mo.

[] Term: 14 Years

[21] Appl. No.: 436,603

[22] Filed: Oct. 25, 1982

[52] U.S. Cl. D2/310; D2/275;
D2/314

[58] Field of Search D2/308, 309, 310, 275,
D2/311, 312, 313; 36/113, 114, 83-84, 136
